US00D677747S

(12) **United States Design Patent**
Baudhuin et al.

(10) **Patent No.:** **US D677,747 S**
(45) **Date of Patent:** **** Mar. 12, 2013**

(54) **EXERCISE BICYCLE FRAME**

(75) Inventors: **John R. Baudhuin**, Santa Monica, CA (US); **John C. Cook**, Ventura, CA (US)

(73) Assignee: **Mad Dogg Athletics, Inc.**, Venice, CA (US)

(**) Term: **14 Years**

(21) Appl. No.: **29/374,084**

(22) Filed: **Jun. 30, 2011**

(51) **LOC (9) Cl.** 21-02

(52) **U.S. Cl.** **D21/697**

(58) **Field of Classification Search** D21/662-670, D21/694, 697; 482/51-52, 57-65; 280/261, 280/266, 282, 284, 288.1, 288.3, 304.4, 835; D12/111

(57) **CLAIM**

The ornamental design for an exercise bicycle frame, as shown and described.

DESCRIPTION

FIG. 1 is a right side view of an embodiment of an exercise bicycle frame.

FIG. 2 is a right side view of an embodiment of an exercise bicycle frame.

FIG. 3 is a rear view of an embodiment of an exercise bicycle frame.

FIG. 4 is a front view of an embodiment of an exercise bicycle frame.

FIG. 5 is a bottom view of an embodiment of an exercise bicycle frame.

FIG. 6 is a top view of an embodiment of an exercise bicycle frame.

FIG. 7 is a left rear perspective view of an embodiment of an exercise bicycle frame.

FIG. 8 is a right side view of an alternate embodiment of an exercise bicycle frame.

FIG. 9 is a left side view of an alternate embodiment of an exercise bicycle frame.

FIG. 10 is a rear view of an alternate embodiment of an exercise bicycle frame.

FIG. 11 is a front view of an alternate embodiment of an exercise bicycle frame.

FIG. 12 is a bottom view of an alternate embodiment of an exercise bicycle frame.

FIG. 13 is a top view of an alternate embodiment of an exercise bicycle frame; and,

FIG. 14 is a left rear perspective view of an alternate embodiment of an exercise bicycle frame.
